NEEDLE FEED SEWING MACHINE

Albert C. Peterson, Park Ridge, and Clarence C. Smith, Chicago, Ill., assignors to Union Special Machine Company, Chicago, Ill., a corporation of Illinois

Application March 7, 1950, Serial No. 148,101

15 Claims. (Cl. 112—206)

1

This invention relates to sewing machines of the type provided with a needle bar which is not only reciprocated but is given a lateral movement in the direction of feed to assist in advancing the work. It relates further to a machine of this type provided with a four-motion feed dog and one or more four-motion loopers operating across the line of feed.

A primary object of the invention has been to provide a machine of the foregoing type which is of relatively simple and inexpensive construction and which is reliable in its operation upon a variety of different types of work.

Another object has been to provide a machine of the character indicated in which the danger of needle breakage or spoilage is reduced to a minimum.

A further object has been to provide simple and readily adjustable means for separately and independently regulating the stroke of the various parts which are shifted in synchronism with the feed of the work in the course of stitch formation. In the preferred form of the invention a four-motion feed dog is provided as the main work advancing means and various other parts are shifted concomitantly with the feeding movement of the feed dog. Thus a needle bar carrier is rocked to impart a needle feed action to the work and assist in advancing the same. Also a looper carrier is rocked in the direction of feed to maintain the proper relationship between the looper and the needle as the latter is shifted with the work; this is in addition to a desired needle avoid movement imparted to the looper. Means are provided for varying the extent of movement of each of these devices in relation to the others. Through the independent adjustment of the driving connections for each of the devices, their movements may be co-related to best advantage for the stitching of various types of work. It has been found that in the handling of different type of work, varying in thickness, hardness, smoothness, and other characteristics, different adjustments of the several driving connections are desirable to insure proper coordination of the parts in the formation of stitches of different lengths.

In attaining the foregoing objects, one advantageous feature of the invention is the employment of a single rotary drive shaft which is in the base of the machine. The connections for reciprocating the needle include a long lever extending through the overhanging arm of the frame and pivoted within the latter at substantially its mid-point. Needle feed movements are imparted to the needle bar carrier by connections

2

including a rock shaft extending along the overhanging arm and having its driving and driven ends enclosed within portions of the needle head and the vertical standard of the frame, respectively. This permits effective lubrication of the relatively moving surfaces at the two ends of the rock shaft.

Another important feature of the invention is the provision of needle guarding elements in front of and in rear of the needle when the latter extends through the work, these guards being shifted in synchronism with the needle as the latter receives its needle feed movement. One of the needle guards is mounted on the feed bar and the other on the looper or looper carrier. In a multiple needle machine the first of these guards will cooperate with the plurality of needles while each looper will carry its own needle guard at the opposite side of the needle.

20 A further feature of the invention is the provision of connections directly from the feed rocker to the looper carrier or carriers, these connections being capable of adjustment to vary the rocking movement of the carrier in the direction of feed, relative to the movement of the feed rocker, and adapted to impart a movement to the carrier which is equal to the feed stroke plus an appropriate needle-avoid movement. The arrangement is such that the extent of rocking movement of the feed rocker and looper carrier 25 may be varied jointly but the rocking movement of the looper carrier may also be varied separately.

20 Other objects, features and advantages of the invention will appear from the detailed description of an illustrative form of the same which will now be given in conjunction with the accompanying drawings, in which:

40 Fig. 1 is a view, partly in front elevation and partly in vertical section, showing a sewing machine embodying the invention;

45 Fig. 2 is an end elevational view of the machine as seen from the needle head end, the cover for the needle head being removed and the work support being shown in section to more clearly illustrate the mechanism;

50 Fig. 3 is a view partly in plan and partly in horizontal section through the overhanging arm of the frame of the machine, the needle head cover being removed;

55 Fig. 4 is an enlarged detail view showing the connections for operating a rock shaft in the machine;

Fig. 5 is a view, partially in plan and partially

in horizontal section, showing the mechanism in the base portion of the frame;

Fig. 6 is an enlarged detail view, in vertical section parallel with the main shaft of the machine, showing the looper operating means;

Fig. 7 is an enlarged detail view, in elevation, showing the relationship between the needles and loopers of a multiple needle machine;

Fig. 8 is a vertical sectional view, taken along the line 8-8 of Fig. 5, showing the work feeding and looper mechanisms of the machine;

Fig. 9 is an enlarged detail view, in rear elevation, of the work feeding mechanism, some of the looper mechanism being also shown;

Fig. 10 is a detail view, in plan, of a looper with a needle guard;

Fig. 11 is an elevational view of the looper and needle guard;

Figs. 12 and 13 are plan views of two different forms of throat plate and feed dog which may be used in the illustrative machine;

Figs. 14 and 15 are plan views of different forms of throat plates which may be used in a multiple needle machine embodying the invention;

Figs. 16 and 17 are plan views of feed dogs which may be employed in connection with the throat plates of Figs. 14 and 15, respectively; and

Fig. 18 is a front elevational view of a modified arrangement of multiple needles and cooperating loopers.

Referring now to the drawings, the illustrative machine is of the flat bed type having a frame including a base portion 10 (Fig. 1) with a work supporting surface at its top, a vertical standard 11, rising from one end of the base, and an overhanging arm extending from the top of the vertical standard over the base and terminating in a needle head 13. The base and standard may be integrally connected, if desired, or they may be separable along the line 10a, the two parts being secured together by screws or bolts as disclosed in the patent to Zeier No. 1,843,188, granted February 2, 1932. A rotary drive shaft 14 is mounted in suitable bearings in the base of the frame and carries a combined handwheel and pulley 15 on a portion which extends outwardly from the frame at its righthand end (Fig. 5). This is the only rotary shaft in the machine. A guard 15a (Fig. 1) may be provided over the handwheel if desired.

In the needle head there is mounted, for reciprocatory and vibratory movements, a needle bar 16 carrying a needle 16a at its lower end (Figs. 1 and 2). The needle bar is mounted for reciprocation in suitable bearing extensions of a frame 17 which is pivotally mounted at its upper end near the top of the needle head by means of a stud 18 having screw threaded engagement with a lug 19, depending from the top of the needle head. The frame 17 is thus capable of vibratory movements in a vertical plane parallel with the line of feed. To retain the frame within this plane as it is vibrated, a plate 20 is secured to the outer face of the needle head adjacent the lower end of the frame 17 and this plate extends over the outer face of the frame. A link 21 is pivotally connected with the frame 17 near its lower end by means of a shouldered screw 22. The opposite end of the link 21 is similarly pivotally attached by means of a screw 23 to the lower end of an arm 24 secured, by a clamping sleeve or the like to a rock shaft 25. This rock shaft is journaled adjacent the arm 24 in a bearing sleeve 26 (Fig. 3) carried by a rearward extension 27 of the needle head hous-

ing. At its opposite end the shaft 25 is journaled in a bearing sleeve 28 mounted in a rearward extension 29 of the frame housing, at the upper end of the vertical standard. Within the hollow of the extension 29, which is in open communication with the interior of the vertical standard, there is clamped to the shaft 25 a sleeve 30 which has a horizontally extending arm 31. To assist in holding the shaft 25 against axial movement a collar 32 is secured to it, adjacent the outer end of the bearing sleeve 28.

Arm 31 is provided with an elongated arcuate slot 33 adapted to receive the shank of a ball-pin 34 (Fig. 4) which may be secured in any desired position along the slot 33 by means of a nut 35 (Fig. 3) engaged with threads on the end of the pin. Cooperating with the spherical portion of the ball-pin 34 is a strap 36 at the upper end of a pitman 37. The lower end of this pitman (Fig. 1) carries a strap 38 surrounding a spherical eccentric or crank element 39 secured to or forming part of the shaft 14. Another spherical crank or eccentric 40 on the shaft 14 cooperates with a strap 41 at the lower end of a pitman 42 which has a strap 43 at its upper end surrounding a spherical portion of a ball-pin secured by a nut 44 to a forwardly extending part 45 of a lever 46. The latter is mounted for rocking movement within the overhanging arm by means of a transversely extending shaft or stud 47. At its opposite end the lever 46 has a forwardly extending portion 48 to which is secured, by means of a nut 49, a ball-pin that is surrounded by a strap 50. This is carried at the upper end of a short link 51 which has a similar strap 52 at its lower end cooperating with the spherical surface of a ball-pin projecting laterally from a block 53 secured to the needle bar 16. A pin 54 projects toward the left in Fig. 1 from the block 53 into a guide slot 55 (Fig. 2) extending lengthwise of the frame 17. Pin 54 prevents turning of the needle bar relative to the frame.

It will be apparent that, through the connections above described, the needle bar is reciprocated lengthwise of the frame 17 and the latter is vibrated at the appropriate time to advance and return the needle along the line of feed. The relative timing of the eccentric or crank portions 39 and 40 of the shaft 14 is such that the needle will be advanced in the direction of feed when it extends through the work and it will be restored to its initial position after it has been raised above the work. In this way the needle assists in feeding the work. The provision of the spherical surfaces at the connections between the various elements, as described, permits the desired movement of the parts without binding.

Cooperating with the needle, when it is beneath the work support, is a thread carrying looper 56 (Figs. 1, 5, 8, 10 and 11) adapted to form with the needle a so-called double locked stitch of the type commonly designated No. 401, as indicated in "Federal Standard Stock Catalogue," section IV, part 5, page 9. The cylindrical shank of the looper is secured by a screw 56a in an opening formed in the top of a carrier 57 having a downwardly extending portion 58 connected with a hub or sleeve 59 rockably mounted on a bolt 60. The latter has an enlarged head 60a at one end and is threaded to receive a nut 60b at its other end to maintain the assembly. Bolt 60 is carried by a downwardly extending arm of a sleeve 61 secured by a pair of screws 61a to a rock shaft 62. A ball-pin 63 projects forwardly from the looper car-

rier and is secured thereto by a nut 64. Cooperating with the spherical portion of the ball-pin is a strap 65 at one end of a link or rod 66, the opposite end of which has a strap 67 cooperating with a ball-pin 68 secured by a nut 69 to the upper end of an arm 70. The latter is secured to a rock shaft 71 extending transversely of the base beneath the main rotary drive shaft 14. As shown in Fig. 6, the shaft 71 has secured thereto, directly beneath the shaft 14, an arm 72 which carries a ball-pin 73 cooperating with a strap 74 at the lower end of a pitman 75. The latter carries a strap 76 at its upper end surrounding a spherical eccentric 77 secured to the shaft 14. To facilitate assembly of the parts the main shaft is formed in two sections, 14 and 14a, which are connected together by a coupling 78. As indicated in Fig. 6, the operating parts just described are located within a lubricant retaining housing forming a portion of the base of the frame.

Rocking of the shaft 62, and hence the looper carrier 57, in the direction of feed is effected through direct connections with a feed rocker forming part of the 4-motion feed mechanism of the machine. Accordingly, this feed mechanism will now be described.

Referring particularly to Fig. 9, there is shown a feed rocker 79 secured by screws 80 to a shaft 81. The latter is journaled in suitable bearings 83 and 84 extending upwardly from the bottom plate of the machine frame. Collars 85 and 86, secured to the shaft 81 adjacent the outer faces of the bearings, serve to retain the shaft against axial movement. A feed bar 87 is rockably mounted at the top of the feed rocker and for this purpose it is secured by a screw 88 to a hollow shaft 89 journaled in two upwardly extending arms of the feed rocker. A downwardly extending curved arm 90, integral with the feed bar 87, is pivotally connected with the lower end of a strap 91 surrounding an eccentric 92 carried by the section 14a of the main shaft. Through these connections the feed bar is rocked about the axis of shaft 89 to impart lifting and lowering movements to a feed dog 93. The latter is secured to the forward end of the feed bar by means of a screw 94 which cooperates with a vertically elongated slot to permit vertical adjustment of the feed dog. Feed and return movements are imparted to the feed dog by an adjustable eccentric or crank element 95, which may be shifted to any desired position along a diameter of a disc 95a and cooperates with a strap 96 pivotally connected with the forward end of an arm 97 secured to the feed rocker. This arrangement is similar to that disclosed in the patent to Wohlpart No. 1,817,727, granted August 4, 1931. The rearward end of the arm 97 is formed as a split sleeve 98 arranged to be clamped, by screws or the like, to a rod 99 extending laterally from the feed rocker, as best shown in Fig. 9. It will be apparent that the adjustable eccentric or crank will, through the connections described, cause the feed rocker to rock about the axis of shaft 81 and thereby impart the feed and return movements to the feed bar and feed dog. The extent of such movements may be readily varied by adjusting the position of the element 95.

An arm 100, integral with the split sleeve 98 and extending upwardly therefrom, is provided with a pair of apertures 101 (Fig. 2) adapted to receive a pivot pin or hollow sleeve 102. In Fig. 2 the pivot element is shown in the upper of the

two apertures. It cooperates with a forked portion 103 of a link 104 which extends forwardly and is pivotally connected by means of a bolt 105 with an arm 107. The bolt 105 is adapted to be secured in any desired position along an elongated slot 106 in the arm 107, thus providing for variation of the extent of rocking movement of the latter. Arm 107 is secured to the shaft 62 by means of a forked sleeve 108 at the lower end of the arm. Accordingly, the rocking movements of the arm are imparted to the looper carrier. The arrangement is preferably such that the looper is shifted in the line of feed to an extent greater than the movement of the feed dog. This permits the looper to follow the movement of the feed dog, as well as the feeding movement of the needle, and, in addition, to partake of an extra movement equal to the usual needle avoid movement of a four-motion looper. It will be understood that the extent of rocking movement of the looper in the line of feed may be varied conjointly with the feed stroke of the feed dog by adjustment of the crank element 95. It may also be varied separately and independently of the adjustment of the feed stroke by changing the position of the bolt 105 in the slot 106. Both of these adjustments, moreover, are independent of the adjustment of the needle feed movement of the needle bar which has been explained in relation to Fig. 4.

Means are provided in accordance with the invention for guarding the needle both on its forward side and its rearward side. The guards provided for this purpose not only insure proper cooperation between the needle and looper and prevent injury to these, but also tend to prevent excessive bending of the needle in the course of its needle feed action. The guard cooperating with the forward side of the needle is in the form of a curved finger 109 (Figs. 10 and 11) mounted directly upon the looper. This finger extends laterally in substantially parallel relation to the loop seizing beak of the looper from a plate-like portion 110 which rests on the lower arm of the C-shaped looper. The plate 110 is provided with a small opening adapted to fit over a pin 111 carried by the looper and the guard is secured to the looper by means of a screw 112.

The guard on the rearward side of the needle is in the form of a plate 113 (Fig. 8) adapted to be mounted on the feed bar 87. A pin 114 carried by the plate 113 cooperates with a groove 115 in the side of the feed bar and the plate is secured by means of a screw 116 passing through an opening 117 in the plate, this screw having threaded engagement with the feed bar. The arrangement is such that the plate 113 may be adjusted slightly in relation to the feed bar. At its forward end the plate is bent laterally, transverse to the line of feed, to provide a guard finger or element 119 (Figs. 5 and 8) parallel with the guard finger 109. As shown in Fig. 8 a portion of the plate 113 is cut away to provide access to the screw 94 which secures the feed dog to the feed bar.

It will be understood that, in the operation of the machine, the needle will descend between the fingers 109 and 119 and while the needle is below the work and is shifted rearwardly to produce its needle feed action, the guard fingers will both move rearwardly substantially in synchronism with the needle. If the feed dog should slip in relation to the work and impose a greater work-advancing load on the needle, the finger 109 will lend support to the needle and prevent excessive bending.

Above the work support a presser foot 120 (Figs. 1 and 2) is provided to urge the work yieldingly against the throat plate and feed dog. This presser foot may be of any suitable form and has a shank 121 secured to the lower end of a presser bar 122. The latter is urged downwardly by a spring 123 surrounding the bar and abutting at its upper end against the bottom of an adjustable screw threaded sleeve 124 and at its lower end against a block 125 secured to the presser bar. Any suitable means may be provided for lifting the presser bar whenever desired to remove work or introduce new work. For this purpose, there is illustrated a link 126 secured at one end to the block 125 and at its other end to a horizontally extending arm of a bell crank lever 127 pivotally supported by means of a shouldered screw 128 on a forwardly extending lug 129 of the rear wall of the overhanging arm. A spring 130 normally rocks the bell crank lever 127 in a counterclockwise direction (Fig. 1). A rod or link 131 connected with an upwardly extending arm of the bell crank lever is connected at its other end with a plate 132 secured to a rock shaft 133. The latter is mounted in a suitable bearing in the rear wall of the vertical standard and may be operated in any suitable way by connections from a foot treadle or knee press. Suitable connections for this purpose are shown and described in the pending application of Albert C. Peterson, et al., Ser. No. 58,222, filed November 4, 1948.

Various forms of throat plate may be used depending upon the character of the feed dog employed. In Fig. 12 there is shown a throat plate 137 cooperating with a feed dog 93 which is relatively narrow adjacent the path of the needle. A needle opening 138 is provided in the throat plate and no needle opening is required in the feed dog. In Fig. 13, on the other hand, there is shown a throat plate 139 having simply a rectangular opening through which a feed dog 931 is adapted to pass, this feed dog having a needle opening 140.

Referring now to Fig. 7, there is shown one arrangement of multiple needles and multiple loopers. This should be used when it is desired to provide lines of stitching which are relatively close together. At the lower end of the needle bar an enlarged, transversely extending head 141a is provided to receive a pair of needles 142. The head 141a is inclined both to the direction of feed and to a line transverse thereto, so that the needles may readily cooperate with rather closely spaced loopers 143 and 144 mounted on a single looper carrier 145. The latter has a sleeve-like hub at its lower end mounted on a shouldered screw or bolt 146 carried by a downwardly extending portion of a sleeve 147 secured to a rock shaft 148. The latter is similar to the rock shaft 62 of Fig. 8 and serves to impart the rocking movement to the needle carrier which causes the looper to follow the needle in its needle feed action and also provides the usual needle avoid function. Rocking of the looper carrier 145 about the screw 146, to provide the loop-seizing and shedding operations of the loopers, may be performed by the same type of connections provided for the similar rocking of the looper carrier 57 (Figs. 1, 5 and 8). It will be understood that a needle guard, similar to the element 108 (Fig. 10), may be provided on each of the loopers 143 and 144.

In Fig. 18 there is shown another suitable arrangement of multiple needles and multiple loopers. This arrangement may be employed whenever the spacing between the two lines of stitch-

ing to be formed is adequate. At the lower end of the needle bar a crosshead 149 is arranged directly across the line of feed. This crosshead is adapted to carry a pair of needles 150. Cooperating with the latter are two loopers 151 and 152 which may be of the same form as the looper 56 of the first embodiment described and may carry needle guard elements similar to 109 of Fig. 10.

10 Looper 151 is secured to the upper end of a carrier 153 having a sleeve-like hub 154 at its lower end rockably mounted on a bolt 155 adjustably retained by a slot 156 in a downwardly extending part of a sleeve 157 secured to a rock 15 shaft 621. The latter is adapted to be rocked in the same manner as the shaft 62 of Fig. 1 to cause the loopers to rock in the direction of feed. Looper 152 is similarly secured to the upper end of a carrier 158 having a sleeve 159 20 at its lower end rockably mounted on a bolt 160 secured in any desired position along a slot 161 in the downwardly extending portion of sleeve 157. A link 162 pivotally connected with each of the carriers 153 and 158 serves to couple these 25 for movement in unison. Loop seizing and loop shedding movements are imparted to the loopers by means of a link 163 connected at one end to a ball-pin extending from the carrier 158 and at its other end to a ball pin extending from 30 the upper end of an arm 164 secured to a rock shaft 165. The latter corresponds with shaft 71 of Fig. 1 and may be operated in the same manner.

The throat plate and feed dog cooperating with the mechanism of Fig. 18 may be of any 35 suitable form. For example, a throat plate of the form shown in Fig. 14 may be employed, this being provided with needle openings 167 and a series of elongated rectangular openings through which the various portions of a feed 40 dog 168 (Fig. 16) may pass. Another form of throat plate 169, is shown in Fig. 15, this having merely a series of rectangular openings for the passage of the various sections of a feed dog 170 (Fig. 17). The latter, in turn, has a pair of needle 45 openings 171. The throat plate and feed dog may, of course, assume a variety of other different forms. Those used in connection with the needle and looper arrangement of Fig. 7 will of course, have the needle openings closer 50 together and one will be disposed rearwardly of the other.

It will be understood that the machine embodying the invention is provided with various 55 accessory devices for handling the thread supplied to the needles and loopers and it is also preferably constructed for automatic lubrication of the principal wear receiving surfaces. In general, the lubrication means may be similar to that disclosed in the above mentioned Peterson, 60 et al. application, Serial No. 58,222. However, as shown in Figs. 5 and 9, the bearings for the feed bar 87 may be lubricated, if desired, by wicking 172, formed of felt or the like, which surrounds the shaft 81 adjacent one end of the 65 bearing lug 83 and extends upwardly and then into and through the hollow bore of the shaft 89. Suitable radial apertures may be provided through the wall of this shaft to conduct excess lubricant from the lower bearing to the bearing 70 surfaces at the top of the feed rocker. A plate-like member 173 may be mounted on the shaft 81 to retain the wicking in proper position.

While an illustrative embodiment of the invention and certain modifications thereof have 75 been disclosed in considerable detail, it will be

understood that various changes, in addition to those specifically suggested, may be made in the form, construction, and arrangement of the several parts without departing from the general principles and scope of the invention.

What we claim is:

1. In a sewing machine having a frame with a work supporting base, a vertical standard and an overhanging arm terminating in a needle head and having a single rotary shaft which extends longitudinally of said base, the combination of a reciprocable needle bar, a carrier for said bar pivotally mounted in said needle head for movement of the lower end of said bar along the line of feed, connections from said shaft for reciprocating said needle-bar, and connections from said shaft for rocking said carrier about its pivot, said last mentioned connections including a rock shaft extending along said overhanging arm, an arm secured to said rock shaft in said needle head and a link pivotally connected with said arm and said carrier.

2. In a sewing machine having a frame with a work supporting base, a vertical standard and an overhanging arm terminating in a needle head and having a single rotary shaft which extends longitudinally of said base, the combination of a reciprocable needle bar, a carrier for said bar pivotally mounted in said needle head for movement of the lower end of said bar along the line of feed, connections from said shaft for reciprocating said needle-bar, and connections from said shaft for rocking said carrier about its pivot, said last mentioned connections including a rock shaft extending along said overhanging arm and having its ends enclosed within said standard and said needle head, respectively, means in said standard for driving said rock shaft from said rotary shaft, an arm secured to said rock shaft in said needle head and a link pivotally connected with said arm and said carrier.

3. In a sewing machine having a frame with a work supporting base, a vertical standard and an overhanging arm terminating in a needle head and having a single rotary shaft which extends longitudinally of said base, the combination of a reciprocable needle bar, a carrier for said bar pivotally mounted in said needle head for movement of the lower end of said bar along the line of feed, connections from said shaft for reciprocating said needle-bar, said connections including a lever extending through said overhanging arm and pivoted intermediate its ends within said arm, and connections from said shaft for rocking said carrier about its pivot, said last mentioned connections including a rock shaft extending along said overhanging arm, an arm secured to said rock shaft in said needle head and a link pivotally connected with said arm and said carrier.

4. In a sewing machine having a frame with a work supporting base, a vertical standard and an overhanging arm terminating in a needle head and having a single rotary shaft which extends longitudinally of said base, the combination of a reciprocable needle bar, a carrier for said bar pivotally mounted in said needle head for movement of the lower end of said bar along the line of feed, connections from said shaft for reciprocating said needle-bar, and connections from said shaft for rocking said carrier about its pivot, said last mentioned connections including a rock shaft extending along said overhanging arm and having its ends enclosed within said standard and said needle head, respectively,

means in said standard for driving said rock shaft from said rotary shaft, said means including an arm secured to said rock shaft, an eccentric on said rotary shaft and a pitman connecting said eccentric with said arm secured to said rock shaft, the connection between said pitman and arm being adjustable to vary the effective length of said arm, an arm secured to said rock shaft in said needle head and a link pivotally connected with said arm and said carrier.

5. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a looper in said base mounted for loop-seizing and shedding movements across the line of feed and for rocking movements in the direction of feed, connections from said shaft to said work feeding member including a feed rocker, connections from said feed rocker to said looper for imparting said rocking movements thereto in the line of feed, and connections from said shaft to said looper for imparting loop-seizing and shedding movements thereto.

6. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a looper in said base mounted for loop-seizing and shedding movements across the line of feed and for rocking movements in the direction of feed, connections from said shaft to said work feeding member including a feed rocker, connections from said feed rocker to said looper for imparting said rocking movements thereto in the line of feed, said last mentioned connections including means for varying the extent of said rocking movement in relation to the movement of said feed rocker, and connections from said shaft to said looper for imparting loop-seizing and shedding movements thereto.

7. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a looper in said base mounted for loop-seizing and shedding movements across the line of feed and for rocking movements in the direction of feed, a feed bar carrying said work feeding member, connections from said shaft for operating said bar to impart four-motion movements to said member and for imparting said loop-seizing and shedding movements and said rocking movements to said looper, and needle guards mounted on said looper and said feed bar, respectively, in front of and in rear of the needle.

11

8. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a looper in said base mounted for loop-seizing and shedding movements across the line of feed and for rocking movements in the direction of feed, connections from said shafts for imparting said four-motion movements to said feed member and said loop-seizing and shedding movements and said rocking movements to said looper, and needle guards disposed in front and in rear of the axis of said needle bar and arranged to be shifted in the direction of feed in coordination with the vibratory movements of said needle bar.

9. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a plurality of needles carried by said needle bar, a plurality of loopers cooperating with said needles in the formation of lines of stitching, means for imparting loop-seizing and loop-shedding movements to said loopers across the line of feed, and means for shifting said loopers in the direction of feed to an extent greater than the movement in the same direction of the cooperating portions of the needles to maintain the desired relationship between the needles and loopers during stitch formation and to provide a needle avoiding movement of the loopers.

10. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a plurality of needles carried by said needle bar, a plurality of loopers cooperating with said needles in the formation of lines of stitching, means for imparting loop-seizing and loop-shedding movements to said loopers across the line of feed, means for shifting said loopers in the direction of feed to an extent greater than the movement in the same direction of the cooperating portions of the needles to maintain the desired relationship between the needles and loopers during stitch formation and to provide a needle avoiding movement of the loopers, and means for independently varying the extent of the vibratory movement of the needle bar and the rocking movement of the loopers.

11. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary

75

12

drive shaft, the combination of means operated by said shaft for imparting reciprocatory and vibratory movements to said needle bar, a plurality of needles carried by said needle bar, a plurality of loopers cooperating with said needles in the formation of lines of stitching, means for imparting loop-seizing and loop-shedding movements to said loopers across the line of feed, connections from said shaft for imparting work feeding and return movements and lifting and lowering movements to said work feeding member, means for shifting said loopers in the direction of feed to an extent greater than the movement in the same direction of the cooperating portions of the needles to maintain the desired relationship between the needles and loopers during stitch formation and to provide a needle avoiding movement of the loopers, means for varying the work feeding and return movements of said work feeding member, and means for separately and independently varying the extent of the vibratory movement of said needle bar and the rocking movement of the loopers.

12. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a plurality of needles carried by said needle bar, a plurality of loopers cooperating with said needles in the formation of lines of stitching, means for imparting loop-seizing and loop-shedding movements to said loopers across the line of feed, means for shifting said loopers in the direction of feed to an extent greater than the movement in the same direction of the cooperating portions of the needles to maintain the desired relationship between the needles and loopers during stitch formation and to provide a needle avoiding movement of the loopers, and needle guards in front of and in rear of said needles in the region of said loopers arranged to be shifted with said needles in the direction of feed.

13. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a plurality of needles carried by said needle bar, a plurality of loopers cooperating with said needles in the formation of lines of stitching, means for imparting loop-seizing and loop-shedding movements to said loopers across the line of feed, means for shifting said loopers in the direction of feed to an extent greater than the movement in the same direction of the cooperating portions of the needles to maintain the desired relationship between the needles and loopers during stitch formation and to provide a needle avoiding movement of the loopers, and needle guards in front of and in rear of said needles in the region of said loopers arranged to be shifted with said needles in the direction of feed, one of said guards being connected with

13

said work feeding member and other of said guards being connected with said loopers.

14. In a sewing machine having a frame with a work supporting base, a vertical standard and an overhanging arm terminating in a needle head and having a four-motion work feeding member in said base, a needle bar mounted in said needle head for reciprocation and for vibratory movement in the direction of feed and a main rotary drive shaft, the combination of means operated by said shaft for imparting reciprocatory and vibratory movements to said needle bar, a looper in said base mounted for loop-seizing and shedding movements across the line of feed and for rocking movements in the direction of feed, connections from said shaft to said work feeding member including a feed rocker, connections from said feed rocker to said looper for imparting said rocking movements thereto in the line of feed, means for varying the extent of the rocking movements imparted to said feed rocker, means for varying the extent of rocking of said looper in relation to the movement of said feed bar, and connections from said shaft to said looper for imparting loop-seizing and shedding movements thereto.

15. In a sewing machine having a frame with a work supporting base, a vertical standard and an overhanging arm terminating in a needle head

14

and having a four-motion work feeding member in said base, a feed-bar carrying said work feeding member, said feed bar being mounted for pivotal and bodily movement, a needle bar mounted in said needle head for reciprocation and for vibratory movement in the direction of feed and a main rotary drive shaft, the combination of means operated by said shaft for imparting reciprocatory and vibratory movements to said needle bar, a plurality of needles carried by said needle bar, a plurality of loopers cooperating with said needles in the formation of lines of stitching, means for imparting loop-seizing and loop-shedding movements to said loopers across the line of feed, and means for shifting said loopers in the direction of feed to an extent greater than the movement in the same direction of the cooperating portions of the needles to maintain the desired relationship between the needles and loopers during stitch formation and to provide a needle avoiding movement of the loopers, said last mentioned means including a connection from said feed bar to said loopers.
